UNITED STATES PATENT OFFICE.

ERLAND PAULSON, OF EMERSON, NORTH DAKOTA.

HAY AND GRAIN LOADER AND CARRIER.

1,188,986.

Specification of Letters Patent. Patented June 27, 1916.

Application filed February 19, 1915. Serial No. 9,294.

To all whom it may concern:

Be it known that I, ERLAND PAULSON, a citizen of the United States, residing at Emerson, in the county of Dunn and State of 5 North Dakota, have invented certain new and useful Improvements in Hay and Grain Loaders and Carriers; and I do hereby declare the following to be a full, clear, and exact description of the invention, such as 10 will enable others skilled in the art to which it appertains to make and use the same.

My invention relates to improvements in hay and grain loaders and carriers, of the type generally designated as "buckers", and 15 is in the nature of an improvement or modification of my co-pending application filed November 2nd, 1914, under S. N. 869,800.

To the above end, generally stated, the invention consists of the novel devices and 20 combinations of devices hereinafter described and defined in the claims.

In the accompanying drawings, which illustrate the invention, like characters indicate like parts throughout the several views.

25 Referring to the drawings, Figure 1 is a side elevation of the improved loader and carrier, some parts being indicated in different positions by means of broken lines, some parts being broken away and some of the 30 exposed parts being shown in sections; Fig. 2 is a plan view of the improved loader and carrier; Fig. 3 is a front elevation of the improved loader and carrier, on an enlarged scale, some parts being broken away and 35 some of the exposed parts being shown in section; Fig. 4 is a longitudinal vertical section taken on the irregular line X⁴—X⁴ of Fig. 2, on an enlarged scale, some parts being broken away and some parts being indicated in different 40 positions by means of broken lines; Fig. 5 is a longitudinal vertical section taken on the line X⁵—X⁵ of Fig. 2, some parts being broken away and some parts being indicated in different 45 positions by means of broken lines; Fig. 6 is a detail view, partly in elevation and partly in section, taken on the line X⁶—X⁶ of Fig. 5, on an enlarged scale; Fig. 7 is a detail view in plan taken in the vicinity of the arrow marked on Fig. 5, on an enlarged scale, some parts being broken away; Fig. 8 is a detail view partly in side elevation and partly in vertical section taken on the line X⁸—X⁸ of Fig. 2, on an enlarged scale, some 50 parts being broken away; Fig. 9 is a plan view of the parts shown in Fig. 8; Fig. 10

is a detail view partly in side elevation and partly in vertical section taken on the line X¹⁰—X¹⁰ of Fig. 2, on an enlarged scale; Fig. 11 is a detail view, partly in elevation and partly in vertical section taken on the line X¹¹—X¹¹ of Fig. 2, on an enlarged scale; Fig. 12 is a transverse vertical section taken on the line X¹²—X¹² of Fig. 1, on an enlarged scale; and Fig. 13 is a longitudinal horizontal section taken on the line X¹³—X¹³ of Fig. 1, on an enlarged scale.

The truck frame of the improved hay and grain loader and carrier is in the form of a horizontal push pole 1, the front end of 70 which is in the form of a fork 2. The push pole 1 is constructed from a pair of horizontally spaced, forwardly diverging angle bars 3, the vertical flanges of which are turned toward each other, as best shown in 75 Fig. 12. At its forward end the push pole 1 is rigidly secured to the intermediate portion of a relatively long, transversely extended angle tie bar 4, the ends of which are rigidly secured to the prongs 5 of the fork 2, at the junction of its head 6 therewith. Transversely extended platform sills 7 connect the rear end portions of the frame bars 3 and support a relatively small platform 8. To the marginal edge of this platform 8 is 85 secured an angle iron, the vertical flange of which extends above said platform and affords a guard 9.

The fork head 6 is transversely divided and the members thereof bent so as to converge rearwardly and their inner ends are rigidly secure, one to each of the frame bars 3. Extended parallel to each fork prong 5, but spaced horizontally inward therefrom is a supplemental fork prong 10. The front 95 ends of these supplemental fork prongs 10 are connected to the respective fork prongs 5 by angle bars 11 and the rear end portions thereof are rigidly secured to the tie bar 4 and the fork head 6.

The fork 2 of the truck frame is supported by a pair of axially aligned wheels 12 mounted, one between each fork prong 5 and its supplemental fork prong 10, as best shown in Fig. 2. Each wheel 12 is mounted 105 on a short axle 13, journaled in bearings 14 on the respective fork prongs 5 and 10. The rear end portion of the push pole 1 is supported by a single steering or caster wheel 15, journaled in a center bracket 16. 110 The shank 17 of the caster bracket 16 has a rectangular socket and is sealed in a

bearing head 18, rigidly secured to and between the frame bars 3 and projects above the platform 8. A collar 19 on the shank 17 is held in position by a set screw 20 and prevents said shank from moving downward in the bearing head 18. Mounted in the socket of the shank 17 is a square steering post 21 on the upper end of which is secured an operator's seat 22. As shown in Fig. 5 the set screw 20 extends into the socket of the shank 17, impinges against the post 21 and holds the operator's seat 22 supported on said post in different vertical positions above the platform 8.

15 The machine is steered by an operator sitting on the seat 22 with his feet resting on the platform 8. Obviously, the operator, by throwing his weight to one side or the other of the machine may oscillate the steering post 21 and hence the wheel 15 to guide the machine.

20 On the periphery of the wheel 15 is formed a rib or flange 23 which cuts into the ground and prevents said wheel from sluing.

25 The machine is pushed in front of the draft animals attached to a pair of whiffle trees 24 secured to a draft equalizer 25. This draft equalizer 25 is attached to the machine by a clevis 26 integrally formed with a cross-head 27 mounted, for a limited sliding movement, between and upon the vertical flanges of the frame bars 3 under the platform 8. The cross-head 27 is secured in its two extreme positions by a

30 gravity held lever 28 having a pair of reversely formed lock lugs 29, arranged to engage opposite ends of said cross-head. The lock lugs 29 are lifted out of engagement with cross-head 27 by a foot lever 30, fulcrumed on a bearing 31 secured to the platform 8 and attached to the lever 28 by a short link 32. The purpose of thus attaching the draft equalizer 25 to the truck frame will presently appear.

35 If it is desirable to use four horses instead of two for pushing the machine another pair of whiffle trees 33 may be added by increasing the length of the draft equalizer 25. As shown the length of the

40 draft equalizer 25 is increased by detachably connecting thereto supplemental sections 34, to which the whiffle trees 33 are attached.

45 Supported from the truck frame, below the fork 2 thereof, is a pick-up platform in the form of a substantially horizontal, forwardly projecting fork. This pick-up platform comprises a multiplicity of laterally spaced pick-up bars or teeth 35, a rock

50 shaft 36, laterally spaced side boards or runners 37, and an angle tie bar 38. The pick-up teeth 35, as shown, are tubular in form, have cast points 39 secured in their forward ends and have their rear end portions bent to curve upward. As shown, the

rock shaft 36 is in the form of an angle bar and the ends of the pick-up teeth 35 are seated directly against one flange thereof and the other flange thereof rests directly on top of said teeth and is secured thereto by U-bolts 40. The pick-up teeth 35 rest directly on the horizontal flange of the tie bar 38, at points substantially where said teeth start to curve upward and are secured thereto by U-bolts 41.

55 A plurality, as shown four, of laterally spaced, two-part flanged hubs 42 embrace the rock shaft 36 and are rigidly secured thereto, by nut equipped bolts 43 passed radially through said hub and the vertex of said rock shaft. The flanged hubs 42 are journaled in bearing straps 44 secured to the tie bar 4 of the truck frame. The rear end portions of the runners 37 are suspended from, and rigidly secured to the rock shaft 36 by angle brackets 45 (see Fig. 1). These runners 37 are also rigidly secured to the ends of the tie bar 38.

60 To the forward end of each supplemental fork prong 10 is rigidly secured a channel post 46, the flanges of which are turned toward each other. Braces 47 connect the channel posts 46 to the fork prongs 5 and the respective flanges of the channel posts 46 are connected, at their intermediate portions, by a pair of horizontal tie bars 48. Diagonal brace bars 49 connect the tie bars 47 with the post 46 at points above and below said tie bars. The outer or free end portions of the pick-up platform are raised 65 and lowered and supported in different vertical positions by a latch lever 50, a co-operating lock segment 51 on the platform 8, and a cable 52. This cable 52 is connected to the lever 50 by a relatively long 70 eye bolt 53. This eye bolt 53, at its head end, is slidably mounted in a swivel block 54, secured to the lever 50 and its eye or head affords a stop to limit the sliding movement of said bolt toward the front of 75 the machine. Swiveled on the threaded end of the bolt 53 is a T-block 55, having a pair of diametrically opposite perforations. The cable 52 is secured, at its intermediate portion, to this T-block by passing its ends through 80 the perforations therein. (See Fig. 7). The nut 56 on the bolt 53 affords an abutment for the T-block 55 under a drawing action on the cable 52. The ends of the cable 52 are extended forward between a pair of 85 guide sheaves 57, journaled on bracket 58 secured to the frame bars 3 (see Fig. 2). From the guide sheaves 57 the cables 52 are extended in reverse directions transversely of the machine, and over guide sheaves 59, 90 from thence toward the front of the machine, over guide sheaves 60 and attached to the front ends of the runners 37. The guide sheaves 59 are journaled in bearings 61 on the rear end portions of the supplemental 95

fork prongs 10 and the guide sheaves 60 are journaled in the webs of the channel posts 46 and bearing brackets 62, secured to outer faces of said webs.

5 One end of a cable 63 is secured to the eye of the bolt 53 and the other end thereof, is secured to the clevis 26. The intermediate portion of this cable 63 runs over a guide sheave 64 journaled to the frame bars 3 to 10 the rear of the cross-head 27. Obviously, this cable 63 will permit the pick-up platform to be tilted by means of the hand lever 50, or in case the load on the pick-up platform is too heavy to be raised by hand, it 15 may be operated by horse power. In the latter case the foot lever 30 will be pushed downward to raise the lever 28 and release the cross-head 27. When the cross-head 27 is released the pulling strain on the draft 20 equalizer 25 is shifted from the truck frame directly on to the pick-up platform tilting connections: Under this pulling strain the eye bolt 53 will slide rearward through the swivel block 54, thereby raising the front 25 end of the pick-up platform through the cable connections 52. The free ends of the runners 37 striking the fork prongs 10 afford stops to limit the forward sliding movement of the cross-head 27 on frame bars 30 3. When the cross-head 27 has reached the limit of its forward sliding movement, the lock lug 29, on the free end of the lever 28, drops back of said cross-head and thereby holds the same against rearward sliding 35 movement. In this position of this cross-head 27, the pick-up platform and its load is held in an elevated position. A box 65 having an open top, bottom and front is secured to the frame fork 2 and affords a 40 three-sided receptacle for the hay or grain on the pick-up platform.

To the runners 37 are secured side boards or plates 66 which work just outside of the side of the box 65 and afford depending extensions of the sides of said box. A bottom plate 67 is secured on top of the pick-up teeth 35 and extends from the rock shaft 36 to the tie bar 38. This bottom plate 67 prevents the butt ends of the shocks and the 45 hay from working through the pick-up teeth 35.

The movement of the improved hay and grain loader and carrier is controlled by brakes, arranged to be set on the peripheries 50 of the wheels 2, at will, by the operator. The brake shoes 68 are pivoted on the short arms of a pair of bell cranks 69 pivoted to the fork prongs 5. The long arms of the bell cranks 69 extend rearward and each has 55 attached thereto a cable 70. These cables 70 are extended toward each other, passed over a pair of vertically spaced guide sheaves 71, journaled to the right hand frame bar 3, and attached to the forward end of a brake 60 rod 72. The rear end of this brake rod 72

is attached to a hand lever 73, fulcrumed to a latch segment 74 having ratchet like teeth with which said lever is adapted to engage by a lateral springing action. Coiled 70 springs 75, surrounding the cables 70, are compressed between the long arms of the bell crank 69 and the supplemental prongs 10 and yieldingly hold the brake shoes 69 out of the engagement with the wheels 12.

In bucking a load of hay, flax or a shock 75 of grain, the same is packed into the box 65 and supported on the pick-up platform. To prevent the load from falling forward, there is provided a vertically movable gate, comprising a cross-bar 76 and a multiplicity of 80 laterally spaced depending tines or long pointed teeth 77. These tines 77 are passed vertically downward through perforations in the cross bar 76 and their upper ends are bent laterally to afford heads which engage 85 the cross-bar 76 and prevent said tines from being pulled therethrough. A channel plate 78 is bolted over this upper edge of the cross-bar 76 and prevents the tines 77 from working up through said cross-bar. On the 90 lower edge of this cross-bar 76 is a reinforcing plate 79 and through which plate the tines 77 project. The ends of the cross-bar 76 terminate short of the post 46 and have bolted thereto horizontally extended U 95 shape straps 80, the prongs of which embrace the cross-bar 76 and the transverse portions of which extend into the channels of the post 46 and guide the cross-bar 76 for vertical sliding movement.

The gate 76-77 is raised and lowered by cables 81 and 82 simultaneously with the raising and lowering movements of the pick-up platform but in reverse directions thereto; in other words, when the pick-up platform is lowered, the gate is raised and when the pick-up platform is raised, the gate is lowered. Journaled between the upper brace bars 49, is a pair of differential pulleys 83. The cables 82 have one of their 110 ends attached to eye bolts 84, secured to the cross-bar 76 and their other ends arranged to be wound onto the large faces of the differential pulleys 83. The cables 81 have one of their ends secured to the free ends of the runners 37 and their other ends arranged to be wound on the small faces of said differential pulleys. As is evident by these connections, when the pick-up platform is lowered, the gate will be raised at a greater speed 115 than the movement of the pick-up platform and when the pick-up platform is raised, the gate will be lowered.

To remove the load from the machine, the same is deposited on the ground by lowering 120 the pick-up frame, raising the gate and then backing the machine away from the load. In case all of the load is not removed from the pick-up platform by this method, there is provided a stripper by the use of which 125

the load may be positively forced from the pick-up platform. As shown, this stripper comprises a pair of bars 85 extended transversely of the pick-up teeth 35 and connected by end bars 86 and crossed tie bars 87. The forward ends of the end bars 86 have secured thereto, sleeves 88 slidably mounted on certain of the teeth 35. This stripper is bent longitudinally of the machine to fit the curved rear end portions of the pick-up teeth 35 when in an inoperative position, as best shown in Fig. 10.

To render the stripper operative, the same is anchored to the ground by a pair of heavy teeth 89, the heads of which are bifurcated and the prongs thereof pivoted to the sleeves 88. These anchor teeth 89 are arranged to turn into operative positions under the action of gravity and to dig into the ground under the backing action of the machine, thereby anchoring the stripper and allowing the pick-up platform to move away therefrom. Under this action, the remaining hay or grain on the pick-up platform will be carried therefrom by the stripper. The teeth 89 are held raised and in operative positions by a pair of branch cables 90, attached to a main cable 91 arranged to be wound on a windlass drum 92; secured to a crank equipped shaft 93, journaled in the platform 8 and a bearing 94, secured to the right hand frame bar 3. The shaft 93 is held against rotation in a direction to cause the cable 91 to unwind from the drum 92 by a ratchet wheel 95, secured to the shaft 93 and a coöperating dog 96, pivoted to the platform 8. The branch cables 90 run through guides 97, secured to the tie bar 4 and the main cable 91 runs through a guide 98 on the right hand frame bar 3.

Operation: The pick-up platform is pushed ahead of the draft animals and the machine is steered by the operator in a manner previously described. In bucking a load of hay, flax, or a shock of grain, the pick-up platform and gate are set as indicated, by full lines in the drawings. Under the advance movement of the machine, the pick-up teeth 37 pass through the butt ends of the sheaves of grain, close to the ground. When a sufficient load of hay or grain has been accumulated on the pick-up platform, the operator draws the lever 50 toward him into a position as indicated by dotted lines in Fig. 5. This movement of the lever 50 through the connections 52 and 53 raises or tilts the pick-up platform and lifts the load thereon from the ground; at the same time lowering the gate. The picking up of the hay or grain and lifting the same from the ground is all accomplished without stopping the advance movement of the machine. If the load on the pick-up platform is too heavy to be lifted by hand, the cross-head 27 may be released by pressing downward

on the foot lever 30, thereby causing the draft equalizer to be pulled forward under the pulling strain of the draft animals and the pick-up platform and its load lifted through the connections 52, 53 and 63. As 70 previously stated, the pick-up platform and its load is held raised, by the engagement of the tooth 29, at the free end of the lever 28, with the cross-head 27. To lower the load on the pick-up platform, it is only necessary to step on the foot lever 30, to lift the engaged tooth 29 out of engagement with the cross-head 27, and allow the said platform to drop, under the action of gravity. The lowering movement of the 80 pick-up platform through the connections 52, 53 and 63 will again return the draft equalizer 25 to its normal position. If it is desired to lower the pick-up platform gradually, the lever 50 may be moved from 85 its full line position to its dotted line position, as shown in Fig. 5. In the dotted line position of the lever 50, its swivel block 54 engages the head of the bolt 53 in its retracted position and the lowering movement 90 of the pick-up platform may be regulated by holding on to the lever 50 until it again reaches its full line position, as shown in Fig. 5.

The load on the machine may be carried 95 to a threshing machine, stack or barn. To remove the load from the machine, the same is deposited on the ground by lowering the pick-up platform, raising the gate and then backing the machine away from the load. 100 In case all of the hay or grain is not removed from the pick-up platform, the stripper may be used in a manner previously described. When the load is removed, by means of the stripper, the teeth 89 are lifted 105 out of the ground, after the load is discharged, by tilting the pick-up platform in the manner previously described. Then by rotating the shaft by the crank 93, the cable 91 may be rewound on the drum 92 to return 110 the stripper to the rear of the pick-up platform and raise the teeth 89 into inoperative positions.

When the load is to be stacked or lifted into a hay loft, the same may be dropped 115 directly on to a hay sling, thus avoiding any pitching whatsoever. The gate box 65, side boards 66 and bottom plate 67, all co-operate to prevent any of the hay or grain from dropping from the machine or being 120 blown therefrom while the machine is traveling with the load, thus preventing any waste whatsoever.

What I claim is:—

1. In a machine of the kind described, the 125 combination with a wheel supported frame, of a pick-up platform mounted on the frame, a draft device movably mounted on the frame, connections from the draft device for lifting the pick-up platform and for 130

- holding the same in a lifted position, and common means for locking the draft device to the frame in its two extreme positions.
2. In a machine of the kind described, the combination with a wheel supported frame, of a pick-up platform mounted on the frame, a draft device movably mounted on the frame, connections from the draft device for lifting the pick-up platform, at will, and for holding the same in a lifted position, common means for securing the draft device in its two extreme positions, and a lever operative on said connections, at will, for lifting the pick-up platform independently of the draft device.
3. In a machine of the kind described, the combination with a wheel supported frame, of a pick-up platform mounted on the frame, a draft device movably mounted on the frame, connections from the draft device for lifting the pick-up platform, at will, and for holding the same in a lifted position, means for securing the draft device in its two extreme positions, a lever directly operative on said connections, at will, for lifting the pick-up platform independently of the draft device, and means for locking the lever in a position for holding the pick-up platform lifted.
4. In a machine of the kind described, the combination with a wheel supported frame, of a pick-up platform mounted on the frame, a draft device movably mounted on the frame, connections from the draft device for lifting the pick-up platform, at will, and an operating lever directly engageable, at will, with said connections for lifting the pick-up platform independently of the draft device.
5. In a machine of the kind described, the combination with a wheel supported frame, of a pick-up platform mounted on the frame, a draft device movably mounted on the frame, connections from the draft device for lifting the pick-up platform at will, said connections having an abutment, and an operating lever engageable, at will, with the abutment on said connection for lifting the pick-up platform independently of the draft device.
6. In a machine of the kind described, the combination with a wheel supported frame, of a pick-up platform mounted on the frame, a draft device movably mounted on the frame, connections from the draft device for lifting the pick-up platform, at will, said connections having an abutment, and an operating lever having an abutment through which said connections are free to slide in one position of the lever, the abutment on the lever arranged to engage the abutment on the said connections during the movement of the lever for lifting the pick-up platform, at will, independently of the draft device.
7. In a machine of the kind described, the combination with a wheel supported frame, of a pick-up platform mounted on said frame, a stripper slidably mounted on said pick-up platform and having a pivoted ground engaging anchor tooth, and common means for holding said tooth in an inoperative position and for returning said stripper to its normal position.
8. The combination with a wheel-supported push pole having a fork-like front end, of a pick-up platform mounted on said push pole below the prongs thereof, means for raising and lowering said pick-up platform, a vertically movable gate mounted on the prongs of said push pole, and connections including differential pulleys operated by the raising and lowering movements of said pick-up platform for moving said gate in reverse directions to the movements of said pick-up platform.
9. The combination with a wheel-supported push pole having a fork-like front end, of a pick-up platform mounted on said push pole below the prongs thereof, means for raising and lowering said pick-up platform, a vertically movable gate mounted on the prongs of said push pole, a differential pulley, a cable attached to said pick-up platform and arranged to be wound upon one face of said pulley, and a second cable attached to said gate and arranged to be wound upon the other face of said pulley.
10. The combination with a wheel-supported push pole having a fork-like end, of a pick-up platform mounted on said push pole below the prongs thereof, means for raising and lowering said platform, channel posts secured to the prongs of said push pole, a vertically movable gate comprising a cross-bar, headed tines passed downwardly through the perforations in said cross-bar, and a channel bar embracing the upper edge of said cross-bar and covering the heads of said tines, and means for moving said gate in reverse directions to the raising and lowering movements of said pick-up platform.
11. The combination with a wheel-supported push pole having a fork-like end, of a pick-up platform fulcrumed on said push pole for tilting movement below the prongs thereof, and a box, open at its top, bottom and front, secured to the fork-like front end of said push pole.
12. The combination with a wheel-supported push pole having a fork-like front end, of a pick-up platform fulcrumed on said push pole for tilting movement below the prongs thereof, a box, open at its top, bottom and front, secured to the fork-like front end of said push pole, and side plates carried by said pick-up platform and forming depending extensions of the sides of said box.

13. The combination with a wheel-supported push pole having a fork-like end, of a pick-up platform journaled to said push pole for tilting movement and comprising a 5 rock shaft, a plurality of laterally spaced teeth, and a pair of runners, a box, open at its top, bottom and front, secured to the fork-like frame of said push pole, side plates secured to the runners of said pick-up plat- 10 form and forming depending extensions of

the sides of said box, and a bottom plate secured to said pick-up platform in the vicinity of its rock shaft.

In testimony whereof I affix my signature in presence of two witnesses.

ERLAND PAULSON.
